UNITED STATES PATENT OFFICE.

JOHN J. SCHWOB, OF ST. LOUIS, MISSOURI.

ELEVATOR.

No. 798,928.

Specification of Letters Patent.

Patented Sept. 5, 1905.

Application filed January 16, 1905. Serial No. 241,303.

To all whom it may concern:

Be it known that I, JOHN J. SCHWOB, a citizen of the United States, and a resident of St. Louis, Missouri, have invented certain new and useful Improvements in Elevators, of which the following is a specification, containing a full, clear, and exact description, reference being had to the accompanying drawings, forming a part hereof.

10 My invention relates to improvements in elevators; and it consists of the novel features herein shown, described, and claimed.

In the drawings, Figure 1 is a perspective of an elevator-shaft and an elevator-car embodying the principles of my invention. Fig. 2 is an enlarged inside elevation of the draft-operating mechanism. Fig. 3 is an outside elevation still further enlarged, said view being the reverse of Fig. 2 and parts being 20 broken away to economize space. Fig. 4 is a vertical sectional detail on the line 4-4 in Fig. 3 and looking in the direction indicated by the arrow. Fig. 5 is a horizontal sectional detail on the line 5-5 of Fig. 3 and looking 25 downwardly. Fig. 6 is a cross-section on the line 6-6 of Fig. 8 and looking in the direction indicated by the arrow. Fig. 7 is a perspective of one of the switch-operating levers. Fig. 8 is a perspective upon an enlarged scale, 30 illustrating the construction and operation of one of the switches. Fig. 9 is a perspective of the door-latch. Fig. 10 is an aside elevation of the draft mechanism. Fig. 11 is a cross-section.

35 Referring to the drawings in detail, the elevator-shaft comprises corner-posts 15, 16, 17, and 18, the channel-bar 19, half-way between the posts 15 and 16, and the channel-bar 20, half-way between the posts 17 and 18.

40 The guide-bars 21 and 22 are rigid with the elevator-car 23 and travel up and down in the channel-bars 19 and 20. The spacing-brackets 24 and 25 are attached to the guide-bar 22 and the draft-operating mechanism, 45 comprising a straightway 26, the cam 27 communicating with the ends of the straightway, the upper switch 28, pivotally mounted in position to close the upper end of the straightway and open the upper end of the

50 camway, and vice versa, the lower switch 29, pivotally mounted in position to close the lower end of the straightway and open the lower end of the camway, and vice versa, and means for operating the switches. The

55 bearing-block 30 is located below the junction at the upper ends of the camway 27 and the

straightway 26. A sleeve 31 is rotatably mounted in this bearing-block, and the shaft 32 is rotatably mounted in the sleeve. The switch 28 is fixed upon the inner end of the 60 shaft 32, and a stop 33 extends from the switch into a stop-recess 34, formed in the periphery at the end of the sleeve 31, so as to make a limited amount of lost motion between the sleeve 31 and the switch 28. A 65 coil-spring 35 is mounted upon the sleeve 31, one end of the spring being connected to the sleeve and the other end of the spring being connected to the switch 28, the tension of the spring being exerted to hold the switch 28 70 yielding at one end of the lost motion. A wheel 36 is rigid with the center of the sleeve 31, said wheel having a latching-tooth 37. A coil-spring is mounted upon the sleeve 31, one end of the spring being attached to the 75 sleeve and the other end of the spring being attached to the bearing-block 30, the tension on said spring being exerted in a direction opposite to the tension of the spring 35, said tension being exerted in opposition to the 80 tooth 37. A bell-crank lever 39 is fixed upon the opposite end of the shaft from the switch 28 and at right angles to the switch. A latch 40 is slidably mounted in bearings 41, extending inwardly from the bearing-block 30 85 in position to engage the tooth 37, and the spring 42 holds the latch yieldingly against the periphery of the wheel 36.

A switch 29 is mounted upon its shaft 43 in a bearing-block 44 above the junction of 90 the lower ends of the camway with the straightway, and the bell-crank lever 45 is fixed upon the inner end of the shaft at right angles to the switch. The rod 46 connects the bell-crank levers 39 and 45, so that the 95 switches 28 and 29 will operate simultaneously, so that when the upper end of the camway is closed by the switch 28 the lower end of the camway will be closed by the switch 29, and vice versa. 100

The cord 47 is attached to the latch 40 and extends downwardly under a guide-roller 48 to a foot-lever 49, said foot-lever being in convenient position for the operator, so that when the foot-lever is pressed the cord 47 is 105 pulled to release the latch 40 from the tooth 47.

A shaft 50 is mounted through the lower part of the bearing-block 30. A crank-arm 51 is fixed upon the inner end of the shaft, and an operating-arm 52 is fixed upon the outer 110 end of the shaft, said arms 51 and 52 being in horizontal alignment in opposite direction

and the arm 52 being immediately in front of the camway 27. A shaft 53 is mounted through the lower bearing-block 54. A crank-arm 55 is fixed upon the inner end of the shaft, and an operating-arm 56 is fixed upon the outer end of the shaft, said arms being normally in horizontal positions and extending in the same direction and the arm 56 being in front of the camway. A rod 57 connects the arms 51 and 55, and a rod 58 connects the arm 51 to the arm 39, so that the switches may be closed by operating the arm 52 upwardly or the arm 56 downwardly. The lower end of the rod 58 is slidingly connected to the arm 51, so that when the arm 52 swings downwardly the switches will not be moved or when the arm 52 swings upwardly the switches will be moved to their closed positions. The lower end of the rod 57 is slidingly connected to the arm 55, so that when the arm 56 swings upwardly the switches will not be moved and when the arm 56 swings downwardly the switches will be moved to their closed positions.

25 The draft-block 59 is mounted between the channel-bars 60 and 61, the channel of said bars being toward each other and said channel-bars being mounted horizontally between the posts 17 and 20, one set of bars for each 30 floor or landing. A roller 62 is mounted at each corner of the draft-block, said rollers operating in the channels of the bars 60 and 61, so as to provide antifriction-bearing for the draft-block and so that the draft-block 35 will move back and forth between the channel-bars. Arms 63 and 64 extend outwardly and downwardly from the draft-block 59, one on each side of the channel-bar 61, and the spring-seat 65 is mounted vertically between 40 said arms. A rod 66 extends from the pulley-frame 67 through the spring-seat 65. A spring-seat 68 is mounted upon the end of the rod, and the spring 69 is mounted upon the rod between the spring-seats 65 and 68. A groove-pulley 70 is mounted in the pulley-frame 67. A groove-pulley 71 is mounted in the pulley-frame 72, said frame being attached to the post 20, and an eye 73 is attached to the post 20. A cord 74 is attached to the eye 73 and 45 extends around the pulley 70, around the pulley 71, over the guide 75, to the latch-bar 76.

The lug 77 projects inwardly from the center of the draft-block 59. A roller 78 is placed 50 endwise against the lug 77, and a cap-screw 79 is inserted through the roller and screw-seated in the lug to form a pintle for the roller, the head of the cap-screw being recessed into the roller.

55 A bearing-block 80 is secured to the door 81 near its rear edge, and a second bearing-block 82 is secured in horizontal alinement of the bearing-block 80 in front of the door, and the latch-bar 76 is slidingly mounted in these 60 bearing-blocks, the bearing-block 82 being

elongated up and down, so as to allow the inner end of the latch-bar to vibrate. A lever 83 is pivotally connected to the inner end of the latch-bar and to the door, said lever being inclined to an angle about forty-five degrees 70 relative to the latch-bar, the upper end of the lever being nearer to the outer end of the latch-bar than the lower end. A spring 85 connects the lever 83 to the door, the tension of the spring being exerted to hold the latch-bar down in its forward position, so that when a quick movement is applied to the cord 74 it will slightly pull the latch-bar outwardly, and as the latch-bar moves outwardly the lever 83 will raise the inner end, thereby disengaging 80 the tooth 86 of the latch-bar from the tooth 87, fixed upon the post 15, so as to unlatch the door. The door 81 is hung at its top by means of common wheeled hangers mounted upon the usual inclined rail. 85

The roller 78 is in position to pass through either the straightway 26 or the camway 27 as the elevator-car moves up and down. Assuming that the switches 28 and 29 are normally in the position shown in Fig. 2—that 90 is, with the camway closed—then the roller 78 will pass up and down through the straightway 26, and the doors 81 will not be opened. If the operator desires to open a door, he will press the foot-lever 49, thereby releasing the 95 latch 40 from the tooth 37 and allowing the tension of the spring 38 to move the switches and close the straightway. Then the roller 78 will pass downwardly into the camway 27 and operate the draft-block 59 to the left, thereby 100 pulling the cord 74, moving the latch-bar to the right, disengaging the tooth 86 from the tooth 87, bringing the lever 83 against the bearing-block 82, and moving the door to its open position. Then as the roller 78 passes 105 outwardly past the center of the camway 27 the cord is released and the door allowed to close, which it does by the action of gravity, and as the roller passes the arm 56 said arm will be swung outwardly, thereby moving the 110 switches to their normal positions with the latch 40 in engagement with the tooth 37 and the straightway open. When the elevator-car passes upwardly, the roller 78 will pass into the lower end of the camway 27, and 115 therefore open the door, and as said roller continues to move upwardly it will swing the lever 52 upwardly and return the switches to their normal position. 120

I claim—

1. In an elevator: a car; a gate; a draft-block; a connection between the gate and draft-block; a straightway carried by the elevator-car and normally open; a camway also carried by said car; switches controlling the 125 straightway and camway; means whereby the operator throws the switches when desired; and means whereby the elevator-car restores the switches to their normal position.

2. In an elevator: a car; a gate; a draft- 130

block; a connection between the gate and draft-block; whereby the movement of the draft-block opens the gate; a cam normally out of action; means whereby the operator 5 puts the cam into action to move the draft-block; and means whereby the passage of the elevator-car up and down puts the cam out of action.

3. In an elevator: a car; a gate; a latch for 10 the gate; a draft-block; a connection between the latch and the draft-block; a connection between the latch and the gate; a cam carried

by the elevator-car and normally out of action; means whereby the operator places the cam in action so as to release the latch and open 15 the gate; and means whereby the passage of the elevator-car puts the cam out of action.

In testimony whereof I have signed my name to this specification in presence of two subscribing witnesses.

JOHN J. SCHWOB.
